UNITED STATES PATENT OFFICE.

WILLIAM DICKINSON, OF SPOKANE, WASHINGTON.

ROCKING-HORSE.

1,348,785.

Specification of Letters Patent. Patented Aug. 3, 1920.

Application filed February 20, 1919. Serial No. 278,108.

To all whom it may concern:

Be it known that I, WILLIAM DICKINSON, a citizen of Canada, having declared my intention to become a citizen of the United States, and a resident of Spokane, in the county of Spokane and State of Washington, have invented a new and Improved Rocking-Horse, of which the following is a full, clear, and exact description.

10 The present invention relates to furniture, and has for an object to provide an article of furniture for the use of children.

The nature and objects of the invention will be more fully set forth in the following 15 specification and illustrated in the accompanying drawings forming part thereof, in which—

Figure 1 is a side view of an attachable seat and hobbyhorse;

20 Fig. 2 is a plan view thereof;

Fig. 3 is a sectional view taken on the line 3—3 of Fig. 4, looking in the direction of the arrow; and

25 Fig. 4 is a side view of the rockingchair with the hobbyhorse attached thereto.

In the illustrated embodiment of the invention, a chair 1 has an arm formed to provide a small seat for a child, the seat being so positioned upon the arm that there will be no undue interference with the comfort of the child sitting in the chair. Preferably the seat is made detachable in order that when not in use it may be removed, and in the illustrated embodiment the seat is made 35 entirely separate from, and as an attachment to be applied to, the chair; and accordingly it may be applied to any suitable chair and sold as a separate article of furniture.

As shown, the attachment consists of a 40 board 2 which is hollowed, as indicated at 3, 3 in Fig. 2, to provide a narrow portion, thus forming a comfortable seat 4 for a child. Forward of the seat and within convenient reach is positioned an upright 5 formed to simulate a horse's head. Projecting laterally from opposite sides of the upright a crossbar 6 provides a handhold within convenient reach of the seat 4 and forward thereof. In the embodiment illustrated, the seat is so positioned upon the chair arm that "forward" of the seat is "forward" of the chair. Obviously, the seat may be reversed so that "forward" of the seat is "rearward" of the chair.

55 In order to provide a convenient means

for securing the attachment to a chair, a clamp is provided which is formed to securely clamp the arm of a chair. The clamp shown consists of an arm 7 rigidly secured, as by means of a screw 8, to the seat and formed to extend parallel thereto and approximately to the center of the seat. A clamping screw 9 is threaded through the end of the arm and preferably is provided with a washer to engage beneath the arm 65 of the chair.

In order to protect the furniture to which the attachment is applied, a fabric facing 10 is provided on the underface of the seat.

Having thus described my invention, I 70 claim as new and desire to secure by Letters Patent:

1. As an article of manufacture, an attachment comprising a board shaped to provide a seat, an upright formed to simulate 75 a horse's head secured to said board forwardly of said seat, and a clamp extending beneath said board to attach the same to the arm of a chair, consisting of an arm extending beneath and parallel to said board 80 but spaced therefrom and a clamp screw threaded through the end of said arm.

2. As an article of manufacture, an attachment comprising a seat, an upright formed to simulate a horse's head forwardly 85 of said seat, and a clamp extending laterally from the side of said seat to secure said seat to the arm of a chair.

3. As an article of manufacture, an attachment comprising a board shaped to 90 provide a seat, an upright formed to simulate the head of a horse secured to said board forwardly of said seat, a handhold projecting from said upright, and a clamp to attach said board to the arm of a chair, 95 comprising an arm extending beneath and parallel to said board, and a clamp screw threaded through the end of said arm beneath the center of said board.

4. The combination with an arm chair of 100 an attachment secured to the arm thereof, comprising a board shaped to provide a seat, an upright formed to simulate the head of a horse and a clamp extending laterally from the side of said seat beneath the 105 arm of said chair securing said attachment to the arm of the chair.

5. As an article of manufacture, an arm chair having an attachment for the arm thereof formed to provide a child's seat, 110

and supporting thereon a handhold positioned to be grasped by a child sitting on said seat.

6. A rockingchair having an arm provided with an attachment formed to provide a small seat, an upright secured to the attachment forward of said seat, and a crossbar secured to said upright to provide a handhold within convenient reach 10 from said seat, substantially as described.

7. A rockingchair having an arm to which is secured an attachment providing a seat, an upright secured to said arm centrally laterally thereof and forward of the seat, 15 providing a handhold within convenient reach of said seat.

8. A rockingchair having an attachment for the arm thereof formed to provide a seat, and an upright secured to said attachment centrally laterally thereof and forward of the seat, said upright being formed to simulate a horse's head. 20

9. A rockingchair having an attachment for the arm thereof formed to provide a seat, and an upright secured to said attachment centrally laterally thereof and forward of the seat, said upright being formed to simulate a horse's head and having handholds projecting laterally from said upright. 25

WILLIAM DICKINSON.
